EYE SET FOR DOLLS

Nicholas Popovich, Teaneck, N. J., assignor of
one-third to Joseph A. Taferner and one-third
to Leo J. Schlitzer, both of New York, N. Y.

Application May 22, 1933, Serial No. 672,116

14 Claims. (Cl. 46—40)

This invention relates in general to eye sets for dolls and artificial figures, including eye members which are mounted within the head of a doll or the like to rotate in eye openings or sockets and simulate natural movement of the eyes as in opening and closing thereof. More particularly the invention relates to eye sets of this character which comprise a supporting means or bar which is secured in the doll head adjacent to the eye opening and on which are mounted eye members and means for holding and rotating them in the eye sockets or openings.

Among the objects of my invention are to provide a supporting means or bar for such eye sets which shall comprise a single piece of metal which is initially of a length less than the distance between opposite side walls of a doll head, which has prongs in its ends to penetrate the material of the head, and which shall embody novel and improved features of construction whereby said bar can be lengthened, elongated or extended within the head to cause said prongs to penetrate the material in the walls of the head and secure the bar in the head; and to provide such a supporting bar which shall comprise a single flat strip of ductile metal having end sections connected by a plurality of extensible rod-like sinuous sections each having a plurality of alternately reversely curved or angularly disposed portions which can be extended or elongated and partially straightened by exerting tension on said end portions tending to separate them, whereby said bar can be lengthened to force said prongs into the walls of a doll head.

Further objects are to provide a novel and improved bracket for mounting eye members on such supporting bar, said bracket to be formed of a single piece of resilient sheet metal shaped to provide bearing notches for an eye member pivot rod and having a spring arm to influence said pivot rod and the eye members carried thereby into the eye sockets; and to provide a novel and improved combination of such a supporting bar and bracket whereby said bracket can be securely fastened upon said bar and clamped between said extensible sections thereof simultaneously with the extension of the bar as the latter is mounted in the doll head.

Difficulty has been encountered heretofore in attaching glass eyeballs to mountings, especially because the eye balls easily crack or chip and cannot be bent, or penetrated with fasteners; but glass eye members are preferable to eye members formed of other material because the glass eye-

balls more closely simulate the natural or anatomical eye and can be more easily made. Therefore, another object of my invention is to provide novel and improved glass eyeball mounting including an eyeball consisting of a segment of a hollow sphere, approximately hemispherical, and a spring clip consisting of a split spring ring embracing and partially surrounding the edges of the eyeball and having a flange overlying the face or spherical surface of the eyeball and lugs overlying the rear or chordal plane surface; to provide such an eyeball mounting wherein said flange of said clip has a segmental spherical portion partially overlying the upper portion of the face of the eyeball to simulate an eyelid; to provide such a structure wherein said clip has integral lugs to slidably receive a pivot rod for rotatably mounting the eyeballs on the supporting bar; and to obtain other advantages and results as will be brought out by the following description.

Referring to the accompanying drawing in which corresponding and like parts are designated by the same reference characters throughout the several views,

Figure 1 is a rear elevation of an eye set embodying my invention, showing it in a doll head which is illustrated in vertical section.

Figure 2 is a transverse vertical sectional view on the line 2—2 of Figure 1.

Figure 3 is a horizontal sectional view on the line 3—3 of Figure 2.

Figure 4 is a detached plan view of the supporting bar showing it in its initial shape by solid lines and in its extended condition by dot and dash lines.

Figure 5 is a composite perspective view of the supporting bar, bracket and eye member supporting yoke, showing them in the relation prior to assembly.

Figure 6 is a perspective view of the rear of one of the eye members.

Figure 7 is an enlarged transverse vertical sectional view through one of the eye members.

Figure 8 is an enlarged transverse vertical sectional view through a modified form of eye member.

Figures 9, 10 and 11 are perspective views of the parts of the eye member shown in Figure 8, and

Figure 12 is a plan view of a modification of the supporting bar.

Specifically describing the illustrated embodiment of the invention the reference character A designates a doll head of known construction which is formed of penetrable material and has

the usual eye sockets B in the face portion thereof. In each of the eye sockets is arranged an eye member 1 mounted to rotate to simulate opening and closing of the eyes, these eye members being 5 mounted on a pivot member or rod 2 which is in turn pivotally mounted in a bracket 3 which is secured on a supporting member or bar 4.

The supporting bar 4 is shown in the form of a flat strip of ductile metal having end sections 5 which are provided with integral prongs 6 for penetrating the material of the doll head. The end sections 5 are connected by an extensible intermediate or central section 7 which consists of a plurality of sinuous rod-like structures each substantially uniform in cross section throughout its length and including a plurality of alternately reversely curved or angularly disposed portions which can be elongated or extended and partially straightened by exerting pressure on the end sections 15 5 tending to separate them, as shown by dot and dash lines in Figure 4. Preferably the sinuous sections 7 merge into each other integrally at their ends and at spaced intermediate points 70 along the longitudinal median line of the bar. 20 The end sections 5 are formed with shoulders 8 each in opposed and aligned relation to one prong 6 to form a bearing point or abutment for a tool for exerting tension on the end sections. The supporting bar is normally of a length less than 25 the distance between the opposite side walls of the doll head, as shown in Figure 4, and in applying the supporting bar to the doll head, tension is exerted on the end sections 5 so as to pull them apart, elongate the bar and drive the prongs 6 30 into the walls of the doll head as shown in Figure 1. The shoulders 8 enable pressure to be applied to the prongs 6 in direct line with the prongs and uniformly on all prongs to avoid twisting of the end sections as the prongs are driven into the 35 doll head. Obviously, the bar will be located adjacent the eye sockets B and in approximately equidistantly spaced relation from each of the eye sockets.

The bracket 3 for supporting the pivot member 45 2, comprises a single strip of resilient sheet metal which is folded on itself and provided with a re-entrant groove 9 at the fold. The free extremities of the strip are disposed in approximately parallel relation and have grooves 10 to receive the central sections 7 of the supporting bar, and notches 100 to straddle one of the junctions 70 of the sinuous sections. The bracket is attached to the supporting bar by inserting the free ends of the strip between the sinuous sections before the 50 bar is elongated, one sinuous section being arranged in the groove 10 of each end and the notches 100 straddling one of the junctions 70; and as the supporting bar is elongated during inserting thereof into the doll head, the sinuous sections are drawn together into the grooves 10 so as to firmly clamp the ends of the bracket strip between them as shown in Figures 1 and 2 of the drawing. The bracket 3 is formed with a slot 12 which extends transversely of the groove 9; and the bracket 3 also has a spring tongue 11 integral therewith and looped outwardly therefrom with its free end extending through said slot 12 transversely of the groove 9.

The reentrant groove 9 of the bracket serves as 70 a bearing for the pivot member 2 which is shown in the form of a rod having its end portions flattened at 13 and disposed in axial alignment with each other, and the pivot rod 2 is inserted into the groove 9 with the spring tongue 11 behind the rod and tending to influence it outwardly of

the groove. The flat ends of the pivot rod slidably support the eye members 1. Each eye member includes an eyeball 14 consisting of a segment of a hollow sphere, preferably formed of glass. Preferably this segment is substantially a hemisphere and has on its spherical surface the representation of a pupil and iris as indicated at 15. The eyeball 14 is mounted on the pivot rod 2 by a spring clip 16 in the form of a split ring that embraces and surrounds the edges of the chordal 10 plane surface 17 of the eyeball a distance substantially greater than half the circumference of said edges. At the ends of the clip 16 and at substantially the center thereof, lugs 18 overlie the chordal plane surface 17 and the clip also has a 15 flange 19 which overlies the spherical surface of the eyeball 14. Also preferably, the flange 19 is extended into a segmental portion 20 which simulates an eyelid and may be used for securing eyelashes 21 to the eyeball between itself and the 20 eyeball as shown in Figure 7. The clip 16 also has diametrically opposite ears 22 which project perpendicularly to the chordal plane 17 and have axially aligned slots 23 to slidably receive the flattened ends 13 of the pivot rod 2. With this construction, the eye members may slide longitudinally of the pivot, but are caused to rotate with the pivot rod. The ears 22 are connected to the clip 16 by reduced bendable neck portions so that by bending these neck portions, the eye member 30 can be angularly adjusted on the pivot rod so as to properly align with or fit the eye sockets.

In assembling the eye set in a doll head, the bracket 3 is attached to the supporting bar 4, and the pivot rod 2 is slipped into the groove 9 of 35 the bracket. Thereafter, the eye members 1 are set in the eye sockets B and the supporting bar 4 is secured in the head. The spring tongue 11 yieldingly influences the eye members into the eye sockets, and the longitudinal movement of the eye members on the pivot rod permits them to adjust themselves to various distances between the eye sockets.

The pivot rod 2 has the usual pendulum arm 45 24 connected thereto for rotating the eyeballs by action of gravity so as to move the eyeballs and the eye sockets into a position to simulate closing of the eyes when the doll is laid horizontally. The pendulum arm is provided with an extension 25 which abuts the spring tongue 11 to limit 50 swinging movement of the pivot rod in the direction to rotate the eye members into open-eye position, the spring tongue 11 thus serving as a shock absorber or buffer.

Instead of the eye members shown in Figures 1 to 7 I may utilize an eye member such as is shown in Figure 8 and which comprises two segments, 26 and 27, of a hollow sphere, each less than a hemisphere. One segment 27 has the representation 28 of an iris thereon and has at 55 one edge a flange 29 which is clamped in a groove 30 in the other section 26, whereby the two sections are connected together. The groove 30 is formed by stamping the metal of the section 26, and the flange 29 can be clamped in the groove 65 by squeezing the walls of the groove together. This joint between the two sections 26 extends horizontally transversely so as to simulate the edge of an eyelid, and of course the section 26 may be flesh-colored. The construction is particularly advantageous in that it facilitates the mounting of eyelashes on the eye member. These lashes are shown as comprising a strip 32 of suitable material, for example tape, to which hairs 33 are glued or otherwise secured. The strip 32 75

is curved correspondingly to the curvature of the groove 30 and is clamped in said groove in juxtaposition to the flange 29 of the section 27 as clearly shown in Figure 8. With this construction, the hairs or lashes 33 are caused to project outwardly from the eye member in close simulation of natural lashes. This avoids the necessity of molding or shaping the lashes as shown in Figure 7 and greatly reduces the possibility of the lashes following the contour of the spherical surface in such a way as to conceal the representation of the iris.

This eye member has diametrically opposite ears 34 formed with openings 36 to receive the pivot rod, disposed perpendicularly to the chordal plane surface of the eye member and connected at one end to the eye member as at 35 so that the ear can be easily moved in its own plane by bending or twisting the portion 35 to angularly 20 adjust the eye member on the pivot member 2 to accommodate irregularities in the relations of the eye sockets to each other and to the pivot member.

Preferably the supporting bar 4 is curved longitudinally and is secured in the doll head with the convex side facing the eye sockets B, as shown in Figure 3, whereby the tendency to displacement of said supporting bar by blows on the doll head or dropping thereof, is resisted by the bar. Any 30 tendency of the bar to flex at its middle toward the back of the head will not pull the prongs out of the doll head but will tend to straighten the bar and force the prongs further into the head, while flexing of the bar in the other direction is relatively slight and will be restrained by the bracket 3.

A modification of the supporting bar is shown in Figure 12 where the sinuous sections 700 are unconnected intermediate their ends, and the end sections 500 have openings to receive a tool for extending the bar to force the prongs 600 into the doll head.

While I have shown and described my invention as embodied in certain details of construction it should be understood that this is primarily for illustrating the principles of the invention and that many modifications and changes may be made in the details of construction without departing from the spirit or scope of the invention.

Having thus described my invention what I claim is:

1. In an eye mounting a supporting member comprising a substantially straight flat strip of ductile metal having end sections formed with integral prongs to be embedded in opposite walls of a doll head, said end sections being connected by integral longitudinally extending sinuous rod-like portions spaced apart and lying in the plane of the strip and capable of being partially straightened and extended by tension exerted on said end sections tending to separate them, whereby said prongs can be driven into a doll head and will be held in position in the doll head by the inherent rigidity of the metal of the strip to secure the supporting member in the doll head.

2. In an eye mounting, a pair of eye members, a pivot rod therefor, and a bracket for said pivot rod comprising a single piece of resilient metal folded upon itself to form a reentrant groove at the fold receiving and serving as a bearing for said pivot rod, and means securing the ends of said piece of metal in the doll head, the folds of said bracket which form the reentrant groove being slotted and a spring tongue being carried integrally by the bracket with its free end ex-

tending through said slotted folds across said groove and behind said pivot rod to influence the pivot rod outwardly of the groove.

3. In an eye mounting, a supporting member comprising a single flat strip of ductile metal having end sections formed with integral prongs to be embedded in opposite side walls of a doll head, and a plurality of longitudinal sinuous sections connecting said end sections, each of substantially uniform cross-section throughout its length and capable of being partially straightened and extended by exerting of tension on said end sections tending to separate them, whereby said prongs can be driven into said doll head to secure said supporting member therein, the corresponding ends of said sinuous sections directly integrally merging into each other so that the intermediate portions of said sinuous sections are drawn toward each other as they are extended, a pair of eye members and a pivot member therefor, and a bracket for said pivot member having portions clamped between said sinuous sections for securing said bracket on said supporting member.

4. In an eye mounting, a supporting member comprising a single flat strip of ductile metal having end sections formed with integral prongs to be embedded in opposite side walls of a doll head, and a plurality of longitudinal sinuous sections connecting said end sections, each of substantially uniform cross-section throughout its length and capable of being partially straightened and extended by exerting of tension on said end sections tending to separate them, all portions of said sinuous sections being in substantially the common plane of the strip whereby said prongs can be driven into said doll head to secure said supporting member therein, said sinuous portions having sufficient inherent rigidity so as to maintain the prongs in set position, a pair of eye members and a pivot member therefor, and a bracket for said pivot member having portions mounted between and held by said sinuous sections for securing said bracket on said supporting member.

5. In an eye mounting, a supporting member comprising a single flat strip of ductile metal having end sections formed with integral prongs to be embedded in opposite side walls of a doll head, and a plurality of longitudinal sinuous sections connecting said end sections, each of substantially uniform cross-section throughout its length and capable of being partially straightened and extended by exerting of tension on said end section tending to separate them, whereby said prongs can be driven into said doll head to secure said supporting member therein, the corresponding ends of said sinuous sections directly integrally merging into each other so that the intermediate portions of said sinuous sections are drawn toward each other as they are extended, a pair of eye members and a pivot member therefor, and a bracket for said pivot member having portions to be located between and formed with grooves to receive said sinuous sections whereby when said sinuous sections are drawn together said portions of the bracket are clamped and held between the sinuous sections with the latter in said grooves.

6. In an eye mounting, a supporting member comprising a single flat strip of ductile metal having end sections formed with integral prongs to be embedded in opposite side walls of a doll head, and a plurality of longitudinal sinuous sections connecting said end sections, each of sub-

stantially uniform cross-section throughout its length and capable of being partially straightened and extended by exerting of tension on said end sections tending to separate them, whereby 5 said prongs can be driven into said doll head to secure said supporting member therein, a pair of eye members and a pivot member thereof, and a bracket for said pivot member comprising a single piece of resilient metal folded upon its 10 self and having a reentrant groove at the fold receiving and serving as a bearing for said pivot member, the ends of said piece of metal being clamped between said sinuous sections for securing the bracket to said supporting member.

15 7. In an eye mounting, a supporting member comprising a single flat strip of ductile metal having end sections formed with integral prongs to be embedded in opposite side walls of a doll head, and a plurality of longitudinal sinuous 20 sections connecting said end sections, each of substantially uniform cross-section throughout its length and capable of being partially straightened and extended by exerting of tension on said end sections tending to separate them, 25 whereby said prongs can be driven into said doll head to secure said supporting member therein, the corresponding ends of said sinuous sections directly integrally merging into each other so that the intermediate portions of said sinuous 30 sections are drawn toward each other as they are extended, a pair of eye members and a pivot member therefor, and a bracket for said pivot member comprising a single piece of resilient metal folded upon itself and having a reentrant 35 groove at the fold receiving and serving as a bearing for said pivot member, the ends of said piece of metal to be located between and formed with grooves to receive said sinuous sections, whereby as said sinuous sections are drawn together said ends of said piece of metal forming the bracket are clamped and held between said 40 sinuous sections.

8. In an eye mounting, a supporting means to be secured in a doll head, a pair of eye members and a pivot member for mounting said eye 45 members on said supporting means, each eye member comprising an eyeball in the form of a segment of a sphere, and a spring clip consisting of a split resilient ring surrounding the 50 edge of said eyeball for a distance substantially greater than half the circumference of said edge and having a flange overlying the spherical surface of the eyeball and lugs overlying the chordal plane surface of said eyeball, whereby said 55 eyeball is removably held in said clip, said clip also having diametrically opposite ears formed with alined openings to slidably receive said pivot member.

9. In an eye mounting, a supporting means to be secured in a doll head, a pair of eye members and a pivot member for mounting said eye members on said supporting means, each eye member comprising an eyeball in the form of a segment of a sphere, and a spring clip consisting of a split resilient ring surrounding the edge 60 of said eyeball for a distance substantially greater than half the circumference of said edge and having a flange overlying the spherical surface of the eyeball and lugs overlying the chordal plane surface of said eyeball, whereby said eyeball is removably held in said clip, said clip also having 65 ears for connection to said pivot member.

10. In an eye mounting, a supporting means to be secured in a doll head, a pair of eye members and a pivot rod for mounting said eye members on said supporting means, said rod having a flattened portion for each eye member, each eye 5 member comprising an eyeball in the form of a segment of a sphere, and a spring clip consisting of a split resilient ring surrounding the edge of said eyeball for a distance substantially greater than half the circumference of said edge and 10 having a flange overlying the spherical surface of the eyeball and lugs overlying the chordal plane surface of said eyeball, whereby said eyeball is removably held in said clip, said clip also having diametrically opposite ears disposed in 15 parallel planes perpendicular to the plane of said split ring and formed with alined elongated openings to slidably receive one of said flattened end portions of said pivot rod.

11. In an eye mounting, a supporting member 20 comprising a single flat strip of ductile metal having end sections formed with integral prongs to be embedded in opposite side walls of a doll head, and a plurality of longitudinal sinuous complementary oppositely disposed sections connecting 25 said end sections, each of substantially uniform cross-section throughout its length and capable of being partially straightened and extended by exerting of tension on said end sections tending to separate them, said sinuous sections being connected together at spaced points intermediate 30 their ends along the longitudinal median line of said strip, all portions of said sinuous sections being in substantially the common plane of said strip, said sinuous portions having sufficient inherent rigidity so as to maintain the prongs in set position.

12. The eye mounting set forth in claim 1 wherein said supporting member is curved longitudinally in a single continuous curve, the convex 40 side thereof being toward the doll's eyes.

13. The eye mounting set forth in claim 4 wherein said supporting member is curved longitudinally in a single continuous curve, the convex 45 side thereof being toward the doll's eyes and said bracket projects from the convex side thereof to be located between said supporting member and the face portion of a doll head.

14. In an eye mounting, a supporting means to be secured in a doll head, a pair of eye members and a pivot rod for mounting said eye members on said supporting means, said rod having a flattened portion for each eye member, each eye member comprising an eyeball in the form of a segment of a sphere, and means for connecting 50 said eyeball to said rod consisting of a clip connected to the eyeball and surrounding the edge of said eyeball for a distance substantially greater than half the circumference of said edge and having a flange overlying the spherical surface 55 of the eyeball and lugs overlying the chordal plane surface of said eyeball, whereby said eyeball is removably held in said clip, said clip having diametrically opposite ears disposed in parallel planes and formed with alined openings to 60 slidably receive one of said flattened end portions of said pivot rod, each ear being integrally connected to said clip by a reduced bendable neck portion whereby said neck portion can be bent to angularly adjust the eyeball to fit said eye 65 sockets.

NICHOLAS POPOVICH.
